DESIGN FOR A PICTURE FRAME

James S. Cushman, New York, N. Y., assignor to Cushman & Denison Mfg. Co., New York, N. Y., a corporation of New York

Application July 19, 1944, Serial No. 114,543

Term of patent 14 years

(Cl. D29—20)

To all whom it may concern:

Be it known that I, James S. Cushman, a citizen of the United States of America, residing at New York 21, in the county and State of New York, have invented a new, original, and ornamental Design for a Picture Frame, of which the following is a specification, reference being had to the accompanying drawing, forming part thereof.

In the drawing:

frame showing my new design.

Figure 2 is an end elevational view thereof.

I claim:

The ornamental design for a picture frame,
as shown.

JAMES S. CUSHMAN.
